(57) **CLAIM**

The ornamental design for a universal board removal device, as shown and described.

DESCRIPTION

FIG. 1 is a perspective view of a universal board removal device according to the preferred embodiment showing my new design;

FIG. 2 is a left side elevational view thereof, the opposite side being a mirror image;

FIG. 3 is a bottom plan view;

FIG. 4 is a top plan view;

FIG. 5 is a fragmentary front elevational view, showing the head and the lower portion of the shaft;

FIG. 6 is a fragmentary rear elevational view, showing the head and the lower portion of the shaft;

FIG. 7 is a perspective view of an alternate embodiment of the universal board removing device;

FIG. 8 is a left side elevational view thereof, the opposite side being a mirror image;

FIG. 9 is a top plan view;

FIG. 10 is a bottom plan view;

FIG. 11 is a front elevational view; and,

FIG. 12 is a rear elevational view thereof.
